Specification of Letters Patent.

Patented Jan. 6, 1920.

Application filed November 4, 1918. Serial No. 280,965.

To all whom it may concern:

Be it known that I, GEORGE F. HALL, a citizen of the United States, and a resident of Newark, in the county of Essex and 5 State of New Jersey, have invented new and useful Improvements in Whistles, of which the following is a specification.

This invention relates to whistles adapted to be used as signals upon automobiles, 10 motor boats and so forth, and operated by the compressed gases of the gas engines thereof, as for instance in connection with one of the cylinders of the engine. More particularly, the invention relates to chime 15 whistles of such a type.

The objects of the invention are to secure an improved whistle of simple and inexpensive construction; to obtain a clear tone, and enable the same to be varied as desired; 20 to provide for these purposes a chime whistle; to secure adjusting means accessible from the outside and easily operated; to provide an extensive surface against which to clamp the set screw; to hold the parts 25 against relative movement by the action of opposing screws; to prevent carbon from affecting the whistle or changing its tone; to enable the whistle to be readily applied to any engine, and to be quickly and easily 30 taken apart and put together, and to obtain other advantages and results as may be brought out in the following description.

Referring to the accompanying drawing, in which like numerals of reference indicate 35 the same parts throughout the several views,

Figure 1 is a side view of a whistle embodying my invention applied to a gas engine cylinder, the latter being in section and partly broken away;

40 Fig. 2 is a central longitudinal section of the whistle and its connections;

Fig. 3 is a perspective view of the central pipe-forming member;

Fig. 4 is a perspective view of the base 45 member of the whistle, and

Fig. 5 is a perspective view of the air distributing disk.

In the specific embodiment of the invention shown in said drawing, 1 indicates the 50 base piece of the whistle, cup-shaped and adapted to receive through its neck 2 a blast of air to blow the whistle. In the mouth of the cup-like base is an air-distributing disk 3 which closely approaches 55 at its edges the walls of the chamber 4 of

the base piece and provides thereat an annular space for the air to pass through. This disk 3 is shown mounted upon the end of a tubular extension 5 of the neck of the base piece, which extends centrally through 60 the chamber of the base piece and terminates substantially flush with the mouth thereof, its end being preferably reduced as at 6 to enter a hole 7 in the center of the distributing disk 3 and form a seat 8 therefor. The sides of this tubular extension 5 are apertured as at 9, within the chamber 4, so as to provide for the passage of air to the annular aperture around the distributing disk 3, and the end of it which receives 65 said distributing disk is interiorly threaded to receive the threaded stem 10 of a pipe-forming member 11 which stem thus clamps the distributing disk releasably in place. 70

This pipe-forming member 11 I have shown as providing three radial webs or partitions 12 whose outer edges fit against the inner wall of a tubular body portion 13, said body portion being shown as cylindrical and of a diameter substantially equal to that of the base 1. The body portion is open at its end next the base, and its end edge lies opposite the edge of the mouth of the base, but spaced therefrom, 80 as shown. The pipes formed by the body portion 12 and pipe-forming member 11 are closed, preferably different distances from the end of the body portion next the base, by transverse walls 14, 15 and 16, one of 85 these as 14 being shown at the extreme end of the pipe-forming member and the others nearer the base of the whistle, so as to give different notes.

The outer end of the pipe-forming member 11 has a central threaded stud 17, and the outer end of the tubular body portion 13 is closed and provided with a central hole 18 loosely receiving said stud 17. A suitably adjustable stop, such as the set screw 19 95 working through the end wall 20 of the body portion and adapted to engage the end partition 14 of the pipe-forming member, enables the tubular body portion to be spaced from the base 1 as desired, to adjust 100 the tone of the whistle, and an ornamental nut 21 on the stud 17, outside the end wall of the body portion, serves to lock the latter wherever adjusted. It is to be noted that the set screw 19 is thus provided with an 110

extensive surface against which to bear, so that no particular care has to be exercised to cause the set screw to register with that surface, and there is, also, no tendency for 5 the set screw to slip off of that surface. Furthermore, the screw 19 operates in an opposite direction from the stud and nut, so that one causes the threads of the other to bind, thus obtaining a firm gripping or 10 binding action to hold the parts against displacement or becoming loose. The structure furthermore enables the parts to be clamped without use of any tools, since the set screw may first be turned to desired position and 15 the nut 21 on stud 17 then clamped down tight by hand.

I have shown my improved whistle applied to the priming cock opening of a gas engine cylinder 22, in Figs. 1 and 2, by 20 means of an elbow 23 adapted to connect at one end with said priming opening as by a nipple 24 and threaded at its other end to screw, into the neck of the base piece 1 of the whistle. This elbow 23 has a valve 25 25 normally held closed by a spring 26 but adapted to be opened against the power of said spring by a lever 27 mounted in a bracket 28 at the bend of the elbow. Any suitable draft means, such as a wire 29, is

secured to said lever, so that by drawing 30 upon it the valve 25 is opened and the whistle sounded, while at other times the spring 26 holds the valve closed and the draft means retracted. Any other suitable means for introducing a blast of air, 35 steam, gas or the like to the whistle to sound the same can be employed, however.

Having thus described the invention, what I claim is.

In a whistle of the character described, 40 the combination of a base piece, an air distributing plate providing an air outlet from the base piece, a pipe-forming member secured to said base piece and plate and providing radial webs or partitions next the 45 base piece and transverse webs at the other ends of said radial webs, a tubular body portion telescoping said pipe-forming means, a set screw working through the end of said tubular body portion against the 50 flat surface of the transverse web of said pipe-forming member farthest from the base piece, and means for adjustably clamping the tubular body portion toward the pipe-forming member to engage said set screw 55 with said web.

GEORGE F. HALL.
